ADDING MACHINE OR SIMILAR ARTICLE

Pierre L. Crease, Kettering, and Donald M. Streiff, Dayton, Ohio, assignors to The National Cash Register Company, Dayton, Ohio, a corporation of Maryland

Filed Dec. 15, 1965, Ser. No. 180

Term of patent 14 years

(Cl. D64—11)

FIG. 1

FIG. 2

FIG. 4

FIG. 1 is a front perspective view of an adding machine or similar article, showing our new design;

FIG. 2 is a rear perspective view thereof;

FIG. 3 is a top plan view; and

FIG. 4 is a left side elevational view thereof.

The dominant features of our design reside in the full-line portions of the drawings.

We claim:

The ornamental design for an adding machine or similar article, as shown and described.
